LADY'S GARMENT

Eleanor Williams, Harrison, N. Y., assignor to The
Barbizon Corporation, New York, N. Y., a cor-
poration of New York

Application November 15, 1951, Serial No. 256,459

5 Claims. (Cl. 2—73)

1

This invention relates to an improvement in women's garments and more particularly to an improvement in slips or other undergarments or nightgowns.

An object of the invention is to provide a garment made of a comparatively small number of separate pieces or panels and which when assembled produce a garment having form fitting qualities in the bodice and midriff portion and one whose skirt portion will not ride up on the figure when the wearer is seated. This object is accomplished by providing a garment made essentially of five pieces or panels. The front pieces comprise a bodice panel, a midriff insert panel and a skirt panel while the back comprises a bodice panel and back skirt panel. The front bodice panel is cut on the bias while the front skirt panel and front midriff panel are both cut on the straight of the goods. The grain direction of the midriff panel is preferably at right angles to that in the straight cut skirt panels. Its lengthwise grain is parallel with the body circumference of the wearer. The back skirt panel is also cut on the straight of the goods while the back bodice panel is cut on the bias.

An advantage of providing bias cut bodice panels in conjunction with straight cut skirt and midriff panels is that the bias cut in the bodice panels permits them to cling and mold to the bust and waist lines of a wearer for better fit while the straight cut skirt and midriff panels will not ride up on the figure while the wearer is seated. There is also greater comfort to the wearer in the straight cut skirt and midriff panels and many women prefer this feature because a straight cut skirt and midriff will not ride up and will not cling too closely to the figure when the wearer is either walking or sitting. Also, the straight cut midriff panel holds its shape and does not distort in any manner. Thus it acts as a perfect anchor for the bodice and skirt panels. The combination of the bias cut bodice and straight cut midriff sections with the straight cut skirt provides a molding of the garment in the top portion of the garment to the body of the wearer and gives a straight line silhouette to the skirt part of the figure.

In addition, a feature of the construction is that the seams at the joints between the front and back skirt panels join the front and back panels slightly on the bias. These slightly on the bias joints are advantageous particularly when the wearer is seated because there is then a slight give at each side of the garment. This provides

2

additional comfort and fit in the straight cut skirt.

A further feature and advantage of the invention provided by the bias cut of the back bodice panel is that it is very form fitting.

Another advantage of the bias cut of the front and back bodice panels in combination with the straight cut midriff and skirt panels is that in donning the garment the bodice will give generously when the wearer is slipping it over her shoulders and bust line. The garment, therefore, may be put on without much straining.

A further object and feature of invention is the provision of novel shape to the front midriff panel so that it will lend a flattering line to the wearer's bust and provide a minimizing appearance to the waist line.

A further feature of the invention is the provision of a cross-grain relationship between the bias cut front bodice panel and the straight cut midriff panel. The effect of the cross-grain relationship is to add strength to the waistline part of the garment. The grains may run parallel on the two pieces last mentioned but the cross-grain relationship is preferable.

Other objects and novel features of the invention will become apparent from the following description and the accompanying drawings, wherein:

Figure 1 is a front elevational view of a garment embodying invention as it appears on a wearer;

Figure 2 is a rear elevational view over the garment of Figure 1 as it appears on a wearer;

Figure 3 is a front elevation over the pattern of the front skirt panel;

Figure 4 is a similar elevation of the back skirt panel of the garment;

Figure 5 is an elevational view of the pattern of the front yoke or bodice panel;

Figure 6 is a similar view of the rear yoke or bodice; and

Figure 7 is a similar view of the pattern of the midriff panel.

Referring to the drawing the garment 10 comprises a front skirt panel 11 cut on the straight of the goods or material from which the garment is to be manufactured. The grain direction of cut in the material is indicated by the arrow A as will be observed from Figure 3. The bottom edge 12 of the front skirt panel is curved and the two side skirt edges 13 and 14 taper toward each other from the bottom edge 12 while the top edge is scalloped providing the two concave portions 15 and 16 adjoining the center concave portion 17 at opposite ends thereof. The concave portions

have slits 15a, 16a and 17a for purposes presently to be described.

A rear or back skirt panel 19 is shown in Figure 4 and as denoted by the arrow B is also cut on the straight of the goods or fabric. This back skirt panel 19 has a curved lower edge 20. The two side edges 21, 22 taper toward each other from the bottom edge 20, to the concave top edge 23. This top edge has a slit 23a for purposes to be described.

As seen in Figure 5 the front yoke or bodice panel 24 is cut on the bias (preferably 45° of the goods or fabric from which it is to be made). The bias cut is denoted by the arrow C. This front bodice or yoke panel is scalloped convexly on its lower edge providing the two convex portions 25 and 26 adjoining the center convex portion 27 at opposite ends thereof. The convex portions have slits 25a, 26a and 27a for purposes presently to be described. The side edges 28, 29 taper towards each other from the bottom edge. The top edge 30 has symmetrical zigzag shape as shown.

The back yoke or bodice panel 32 is cut on the bias (preferably 45° of the goods or fabric from which it is made). This bias cut is preferably opposite to that of the bias cut of the front yoke or bodice panel and its direction is indicated by the arrow D. This rear bodice or yoke panel as seen in Figure 6 has a substantially straight bottom edge 33 provided with the slits 33a for purposes presently described. The side edges 34 and 35 flare upwardly from the bottom edge 33 and join the symmetrically arranged zigzag upper edge 36.

The midriff section or panel 38 as seen in Figure 7 is cut on the straight of the goods or fabric from which it is made. This cut is denoted by the arrow E. This grain direction of this panel preferably is perpendicular to the direction of the straight cut of the front skirt panel 11 but in the alternative as indicated by the dotted arrow Ea may run parallel with or in the same direction. This midriff panel has the scalloped lower edge comprising the convex center portion 39 and the adjoining convex portions 40 and 41. The slits 39a and 41a are provided in the bottom edge for purposes presently to be described. The side edges 42 and 43 flare upwardly from the bottom edge and join the concavely scalloped upper edge consisting of the center concave portion 44 joining respectively the flats 45 and 46. These flats 45 and 46 in turn join the concave portions 47 and 48 which respectively meet the side edges 42 and 43. The center concave portion 44 is provided with the slits 44a for purposes presently to be described.

It is understood that appropriate seam allowances are provided in the required edges of the various portions 11, 19, 24, 32 and 38.

The five panels or pieces just described are appropriately joined together by sewing the appropriate meeting edges thereof together. For example, the side edge 14 of the front panel portion 11 is sewed to the side edge 22 of the rear skirt panel portion 19 and the side edge 13 of the front skirt panel 11 is sewed to the side edge 21 of the rear skirt panel 19. Because these side edges taper, there is a relative bias at the respective seams which provides a slight give when the wearer is seated.

The bottom edge 33 of the back yoke or bodice panel 32 is sewed to the upper edge 23 of the back skirt panel 19, and also to the meeting portions of the respective concave sections 15 and 75

16 of the upper edge of the front skirt panel 11. The lower portions 39, 40 and 41 of the midriff panel 38 are sewed respectively to the concave portion 17 and the meeting portions of the concave portions 15 and 16 on the upper edge of the front panel 11. The side edges 42 and 43 of the bodice portion 38 are sewed respectively to the lower parts of the side edges 34 and 35 of the back yoke or bodice panel 32. The side edges 28 and 29 of the front bodice or yoke panel 24 are sewed to the meeting parts of the side edges 34 and 35 of the back yoke or bodice panel 32. The bottom scalloped edge of the front yoke or bodice panel 24 is sewed to the upper edge of the front panel 11. In effecting this sewing the concave lower edge portion 27 of the front bodice or yoke portion 24 it is to be noted is somewhat longer than the corresponding concave section 44 of the front bodice panel 38 and similarly the convex sections 25 and 26 are somewhat longer than the concave portions 47 and 48 of the midriff panel 38. This larger dimension is intended, and in sewing the convex portions 25, 26 and 27 to the corresponding concave portions 47, 48 and 27 the respective sections 25, 26 and 27 are Shirred or gathered at 49. This shirring occurs principally at and symmetrically relative to the cusps between the respective convex scallop portions 25, 26 and 27. This shirring effects the formation of bust cup sections in the front yoke panel 24. The two peaks 45 and 46 of this midriff panel are specially designed and arranged so that they are in a direct line with each bust position thereby enhancing the form of the bust. Each high point is centrally located relative to the alternating shirring 49 on the bodice. Thus there are four lines of alternating shirring for better balance of the bodice panel. Because of these high points 45, 46, the shirring under each bust breaks in two or opposite directions for perfect balance and strain under the bust line. The shirring breaks to the left and to the right maintaining an equal and perfect molding of the bodice.

In all sizes the two points 45 and 46 will be guided so as to be located in the proper position on the midriff panel and located in a direct line below the bust for better form fitting contour. The scalloped formation of the joint between the midriff panel and of the front yoke or bodice panel 24 also facilitates stretching action at the waist line and at the same time permits the garment to mold itself to the waist line of the wearer.

It is to be noted that notwithstanding the fact that both the front skirt panel 11 and the rear skirt panel 19 are cut on the straight, the seams between the respective side edges 14 and 22 and 13 and 21 are slightly on the bias relative to each other because of the sloping nature of the side walls of the two panels. This is advantageous because it provides the slight give at each side of the garment when the wearer is seated.

The slits 15a, 16a, 17a, 23a, 25a, 26a, 27a, 33a, 41a and 44a permit proper fit between meeting edges which are joined together.

The assembled sections just described thus provide a garment in which the upper bodice portion both at the front and back is cut on the bias and joined to a straight cut midriff section and to a skirt portion which both at the front and back is cut on the straight. The bias cut upper panels of the garment tend to mold themselves to the upper part of the wearer's body while the straight cut skirt panels will hang without clinging. The garment also accomplishes all

the objects and features set forth at the outset of this specification.

It is to be understood of course that the peaks of the zigzag upper edges of the front and back panels are joined by the appropriate shoulder straps 50 to suspend the garment from the wearer's shoulders.

While a specific embodiment of the invention has been described, variations in structural detail within the scope of the claims are possible and are contemplated. There is no intention, therefore, of limitation to the exact details shown and described.

What is claimed is:

1. A lady's garment of five fabric panels combined together to form the garment comprising a front skirt panel cut on the straight and having a concavely scalloped upper edge, a curved bottom edge and straight side edges, the latter tapering from the outermost ends of the bottom edge toward the outermost ends of the upper edge, a midriff panel cut on the straight and having a concavely scalloped upper edge, a convexly scalloped bottom edge and straight side edges tapering from the outermost ends of the last-named bottom edge toward the outermost ends of the last-named upper edge, a front bodice panel cut on the bias and having a zig-zag shaped upper edge, a convexly scalloped bottom edge and straight side edges tapering from the outermost ends of the last-named bottom edge toward the outermost ends of the zig-zag shaped upper edge, a rear skirt panel cut on the straight and having a concavely curved upper edge, a convexly curved bottom edge, and straight side edges tapering from the outermost ends of the last-named bottom edge to the outermost ends of the last-named upper edge, and a rear bodice panel cut on the bias and having a zig-zag shaped upper edge, a substantially straight bottom edge and straight side edges flaring from the outermost ends of said last-named bottom edge towards the outermost ends of said last-named zig-zag shaped upper edge, said five panels being joined together along meeting side edges of said front and rear skirt panels, along the meeting upper edge of said front skirt panel and lower edge of said midriff panel and the lower outside edge portions of said rear bodice panel, along the meeting upper edge of said rear skirt panel and the lower middle edge portion of said rear bodice panel, along the meeting upper edge of said midriff panel and the lower edge of said front bodice panel, along the meeting side edges of a portion of said rear bodice panel and said midriff panel and along the meeting side edges of another portion of said rear bodice panel and said front bodice panel to form a garment having a bias cut bodice and a straight cut midriff and skirt.

2. A lady's garment of five fabric panels combined together to form the garment comprising a front skirt panel cut on the straight and having a concavely scalloped upper edge, a curved bottom edge and straight side edges, the latter tapering from the outermost ends of the bottom edge toward the outermost ends of the upper edge, a midriff panel cut on the straight and having a grain direction that is perpendicular to that of the straight cut of said front skirt panel and having a concavely scalloped upper edge, a convexly scalloped bottom edge and straight side edges tapering from the outermost ends of the last-named bottom edge toward the outermost ends of the last-named upper edge, a front bodice panel cut on the bias and having a zig-zag shaped upper edge, a convexly scalloped bottom edge and straight side edges tapering from the outermost ends of the last-named bottom edge toward the outermost ends of the zig-zag shaped upper edge, a rear skirt panel cut on the straight and having a concavely curved upper edge, a convexly curved bottom edge, and straight side edges tapering from the outermost ends of the last-named bottom edge to the outermost ends of the last-named upper edge, and a rear bodice panel cut on the bias and having a zig-zag shaped upper edge, a substantially straight bottom edge and straight side edges flaring from the outermost ends of said last-named bottom edge towards the outermost ends of said last-named zig-zag shaped upper edge, said five panels being joined together along meeting side edges of said front and rear skirt panels, along the meeting upper edge of said front skirt panel and lower edge of said midriff panel and the lower outside edge portions of said rear bodice panel, along the meeting upper edge of said rear skirt panel and the lower middle edge portion of said rear bodice panel, along the meeting upper edge of said midriff panel and the lower edge of said front bodice panel, along the meeting side edges of a portion of said rear bodice panel and said midriff panel and along the meeting side edges of another portion of said rear bodice panel and said front bodice panel to form a garment having a bias cut bodice and a straight cut midriff and skirt.

upper edge, a convexly scalloped bottom edge and straight side edges tapering from the outermost ends of the last-named bottom edge toward the outermost ends of the zig-zag shaped upper edge, a rear skirt panel cut on the straight and having a concavely curved upper edge, a convexly curved bottom edge, and straight side edges tapering from the outermost ends of the last-named bottom edge to the outermost ends of the last-named upper edge, and a rear bodice panel cut on the bias and having a zig-zag shaped upper edge, a substantially straight bottom edge and straight side edges flaring from the outermost ends of said last-named bottom edge towards the outermost ends of said last-named zig-zag shaped upper edge, said five panels being joined together along meeting side edges of said front and rear skirt panels, along the meeting upper edge of said front skirt panel and lower edge of said midriff panel and the lower outside edge portions of said rear bodice panel, along the meeting upper edge of said rear skirt panel and the lower middle edge portion of said rear bodice panel, along the meeting upper edge of said midriff panel and the lower edge of said front bodice panel, along the meeting side edges of a portion of said rear bodice panel and said midriff panel and along the meeting side edges of another portion of said rear bodice panel and said front bodice panel to form a garment having a bias cut bodice and a straight cut midriff and skirt.

3. A lady's garment of five fabric panels combined together to form the garment comprising a front skirt panel cut on the straight and having a concavely scalloped upper edge, a curved bottom edge and straight side edges, the latter tapering from the outermost ends of the bottom edge toward the outermost ends of the upper edge, a midriff panel cut on the straight and having a cross grain direction that is substantially parallel to that of said front skirt panel and having a concavely scalloped upper edge, a convexly scalloped bottom edge and straight side edges tapering from the outermost ends of the last-named bottom edge toward the outermost ends of the last-named upper edge, a front bodice panel cut on the bias and having a zig-zag shaped upper edge, a convexly scalloped bottom edge and straight side edges tapering from the outermost ends of the last-named bottom edge toward the outermost ends of the zig-zag shaped upper edge, a rear skirt panel cut on the straight and having a concavely curved upper edge, a convexly curved bottom edge, and straight side edges tapering from the outermost ends of the last-named bottom edge to the outermost ends of the last-named upper edge, and a rear bodice panel cut on the bias and having a zig-zag shaped upper edge, a substantially straight bottom edge and straight side edges flaring from the outermost ends of said last-named bottom edge towards the outermost ends of said last-named zig-zag shaped upper edge, said five panels being joined together along meeting side edges of said front and rear skirt panels, along the meeting upper edge of said front skirt panel and lower edge of said midriff panel and the lower outside edge portions of said rear bodice panel, along the meeting upper edge of said rear skirt panel and the lower middle edge portion of said rear bodice panel, along the meeting upper edge of said midriff panel and the lower edge of said front bodice panel, along the meeting side edges of a portion of said rear bodice panel and said midriff panel and along the meeting side edges of another portion of said rear bodice panel and said front bodice panel to form a garment having a bias cut bodice and a straight cut midriff and skirt.

other portion of said rear bodice panel and said front bodice panel to form a garment having a bias cut bodice and a straight cut midriff and skirt.

4. A lady's garment of five fabric panels combined together to form the garment comprising a front skirt panel cut on the straight and having a concavely scalloped upper edge, a curved bottom edge and straight side edges, the latter tapering from the outermost ends of the bottom edge toward the outermost ends of the upper edge, a midriff panel cut on the straight and having a concavely scalloped upper edge, a convexly scalloped bottom edge and straight side edges tapering from the outermost ends of the last-named bottom edge toward the outermost ends of the last-named upper edge, a front bodice panel cut on the bias and having a zig-zag shaped upper edge, a convexly scalloped bottom edge having three convex scallops arranged side by side and in which the scalloped upper edge of the midriff panel meeting therewith has three concave scallops arranged side by side for junction with respective of said three convex scallops, the dimensions of said convex scallops being larger than those of said concave scallop and said convex scallops being Shirred adjacent cusps between them so that their junction with the said concave scallops provide perfectly balanced bust cups and said front bodice panel, said front bodice panel having straight side edges tapering from the outermost ends of the said convex scalloped bottom edge toward the outermost ends of the zig-zag shaped upper edge, a rear skirt panel cut on the straight and having a concavely curved upper edge, a convexly curved bottom edge, and straight side edges tapering from the outermost ends of the last-named bottom edge to the outermost ends of the last-named upper edge, and a rear bodice panel cut on the bias and having a zig-zag shaped upper edge, a substantially straight bottom edge and straight side edges flaring from the outermost ends of said last-named bottom edge towards the outermost ends of said last-named zig-zag shaped upper edge, said five panels being joined together along meeting side edges of said front and rear skirt panels, along the meeting upper edge of said front skirt panel and lower edge of said midriff panel and the lower outside edge portions of said rear bodice panel, along the meeting upper edge of said rear skirt panel and the lower middle edge portion of said rear bodice panel, along the meeting upper edge of said midriff panel and the lower edge of said front bodice panel, along the meeting side edges of a portion of said rear bodice panel and said midriff panel and along the meeting side edges of another portion of said rear bodice panel and said front bodice panel to form a garment having a bias cut bodice and a straight cut midriff and skirt.

5. A lady's garment of five fabric panels combined together to form the garment comprising a front skirt panel cut on the straight and having a concavely scalloped upper edge, a curved bottom edge and straight side edges, the latter

5 tapering from the outermost ends of the bottom edge toward the outermost ends of the upper edge, a midriff panel cut on the straight and having a concavely scalloped upper edge, a convexly scalloped bottom edge and straight side edges tapering from the outermost ends of the last-named bottom edge toward the outermost ends of the last-named upper edge, a front bodice panel cut on the bias and having a zig-zag shaped upper edge, a convexly scalloped bottom edge having three convex scallops arranged side by side and in which the scalloped upper edge of the midriff panel meeting therewith has three concave scallops arranged side by side for junction with respective of said three convex scallops, the dimensions of said convex scallops being larger than those of said concave scallop and said convex scallops being Shirred adjacent cusps between them positioned to lie in direct line with respective busts of a wearer and in which said Shirring is symmetrically disposed to the right and left of said cusps, thereby providing a garment in which the bust cups have even strain distribution at each side of the cusps so that uniform bust support occurs, said front bodice panel having straight side edges tapering from the outermost ends of the said convex scalloped bottom edge toward the outermost ends of the zig-zag shaped upper edge, a rear skirt panel cut on the straight and having a concavely curved upper edge, a convex curved bottom edge, and straight side edges tapering from the outermost ends of the last-named bottom edge to the outermost ends of the last-named upper edge, and a rear bodice panel cut on the bias and having a zig-zag shaped upper edge, a substantially straight bottom edge and straight side edges flaring from the outermost ends of said last-named bottom edge towards the outermost ends of said last-named zig-zag shaped upper edge, said five panels being joined together along meeting side edges of said front and rear skirt panels, along the meeting upper edge of said front skirt panel and lower edge of said midriff panel and the lower outside edge portions of said rear bodice panel, along the meeting upper edge of said rear skirt panel and the lower middle edge portion of said rear bodice panel, along the meeting upper edge of said midriff panel and the lower edge of said front bodice panel, along the meeting side edges of a portion of said rear bodice panel and said midriff panel and along the meeting side edges of another portion of said rear bodice panel and said front bodice panel to form a garment having a bias cut bodice and a straight cut midriff and skirt.
